SMOKER'S PIPE

Jerome Gevirmen, Brooklyn, N. Y.

Application February 18, 1955, Serial No. 34,578

Term of patent 7 years

(Cl. D85—8)

FIG-2.

FIG-3.

Fig. 1 is a top plan view of a smoker's pipe, showing my new design;

Fig. 2 is a side elevational view thereof; and

Fig. 3 is a cross-sectional view thereof, to an enlarged scale, taken on line 3—3 in Fig. 2.

I claim:

The ornamental design for a smoker's pipe as shown.
